UNITED STATES PATENT OFFICE.

ERNST W. KOPKE, OF MANILA, PHILIPPINE ISLANDS.

SAVEALL.

Application filed September 19, 1924. Serial No. 738,726.

To all whom it may concern:

Be it known that I, ERNST W. KOPKE, a citizen of the United States, residing in the city of Manila, Philippine Islands, have invented certain new and useful Improvements in Savealls; and I do hereby declare the following to be a full, clear, and exact description of the invention such as will enable others skilled in the art to which it appertains to make and use the same.

The invention relates to a saveall for evaporators and has for its object to provide a simple and efficient device to be built into evaporators under construction, or to be installed in any standard type of evaporator already constructed and in use, with a minimum of expense and labor, that will effectively separate all liquid entrained in the vapors generated in the evaporator and, preferably, return the separated liquid to the boiler section of the evaporator. To these ends the invention comprises a diaphragm adapted to be interposed in the evaporator below or in advance of the vapor outlet thereof, said diaphragm having a central discharge opening and a series of drainage orifices about its marginal edge adjacent the wall of the evaporator, means associated with the central discharge opening to deflect vapors passing through said opening in a whirling course above the diaphragm and toward the wall of the evaporator, said means preferably involving a deflector plate substantially parallel with and located a short distance above the diaphragm and overlying the discharge opening, a series of arcuate deflector blades disposed between the diaphragm and the deflector plate and about the central opening in the former, each of the drainage orifices being provided with a baffle plate overhanging the same, said baffle plates serving to arrest the liquid entrained in the vapors as the vapor laden liquid is directed toward the wall of the evaporator chamber, and to direct the liquid downward through said orifices.

The invention is illustrated in the accompanying drawings in which:—

Figure 1 is a vertical section through the upper part of a typical evaporator, having the saveall applied thereto.

Figure 2 is a section on line 2—2 of Fig. 1.

Figure 3 is an enlarged sectional elevation on line 3—3 of Fig. 2.

Referring to the drawings, 1 indicates the main shell or body portion of a typical

evaporator, such for example as a vacuum pan, which is provided with a conical head section 2 terminating in the discharge neck or outlet 3. Mounted within the cylindrical shell of the evaporator, and preferably near the upper end of said shell and below the outlet 3, is a transverse plate or diaphragm 4, which is fashioned to fit accurately within the shell, which is usually circular in cross section, said diaphragm being secured in position by brackets or angle sections 5. The diaphragm is provided with a relatively large central opening 6 through which the vapors and any liquid entrained therein pass.

The outer peripheral portion of the diaphragm 4 is provided with a series of drainage orifices 9 which are located adjacent the wall of the evaporator shell 1, and secured to the upper face of the diaphragm is a series of baffle plates 10, each of which overhangs a drainage orifice 9, the body portion of each baffle plate being inclined at an angle of substantially 60 degrees to the plane of the diaphragm.

Mounted above the central opening 6 of the diaphragm 4, is a deflector plate 7, which is preferably in the form of a flat disc approximately twice the diameter of the opening 6 and disposed concentrically with the latter, and interposed between the diaphragm 4 and the deflector plate 7, is a series of arcuate vanes 8 which extend from the edge of the diaphragm surrounding the opening 6 to the circular edge of the deflector plate 7, said plates being disposed in circular series about the opening 6, as indicated in Fig. 2.

The operation of the device as described is as follows:

The vapors generated in the boiler section of the evaporator pass at relatively high velocity through the central opening 6 toward the discharge opening 3, and tend to carry with them varying percentages of liquid, depending upon the character of the primary liquid which is being operated upon. The vapors and entrained liquid passing through the opening 6 in the diaphragm 4 impinge upon the deflector plate 7 above the opening 6, which changes the course of the flow of vapor liquid abruptly from a vertical direction toward the outlet 3, to a horizontal direction across the diaphragm 4 and toward the wall of the shell 1. In addition to the change of direction

of flow from a vertical to a horizontal, the vanes 8 impart to the vapors and entrained liquid, a whirling movement so that they sweep over the top surface of the diaphragm 5 at relatively high velocity and impinge on the under inclined faces of the baffle plates 10, which are effective to arrest the liquid carried by the vapor and cause the latter to be discharged downwardly through the 10 orifices 9 into the portion of the evaporator chamber 1 below the diaphragm. The disposition of the baffle plates in peripheral series around the diaphragm 4, and inclined at an angle to directly oppose the centrifugal 15 whirl of the vapors produced by the deflector plate 7 and the arcuate vanes 8, is effective in setting up a relatively strong down-draft through each of the orifices 9, thereby not only insuring a prompt discharge 20 of the separated liquid from the vapors, but also preventing any upward flow of the vapors through said orifices 9. In practical application to vacuum pans or similar devices for sugar juices, the apparatus 25 has been found to be effective in separating and recovering practically the entire liquid content of the vapors, and returning the recovered liquid to the boiler section of the evaporator.

30 Obviously the diaphragm and associated deflector plates 7 and arcuate vanes 8 may be constructed and assembled in various ways, or if desired may be formed as an integral casting. When, however, it is desired 35 to apply the device to an evaporator that has already been installed and in use, the diaphragm may be formed of one or more sheets or sections, or the diaphragm and the associated deflector plates and vanes 40 may be formed of multiple castings which may be individually introduced into the evaporator shell through the usual manhole, and assembled within the evaporator in the general arrangement indicated in the 45 drawings.

What I claim is:

1. A saveall for evaporators comprising a diaphragm adapted to divide the evapo-

rator below the vapor outlet thereof, said diaphragm having a central discharge opening and a series of drainage orifices about its marginal edge adjacent the wall of the evaporator, means associated with the central discharge opening to deflect vapors passing through said opening in a whirling course over said diaphragm and toward the wall of the evaporator, and baffle plates overhanging the drainage orifices to arrest liquid entrained in the vapors and direct the liquid downward through said orifices. 50 55 60

2. A saveall for evaporators comprising a diaphragm adapted to divide the evaporator below the vapor outlet thereof, said diaphragm having a central discharge opening and a series of drainage orifices about 65 its marginal edge adjacent the wall of the evaporator, means associated with the central discharge opening to deflect vapors passing through said opening in a whirling course over said diaphragm and toward the 70 wall of the evaporator, and baffle plates overhanging the drainage orifices inclined in a direction opposite to the movement of the vapors to arrest liquid entrained in the vapors and direct the liquid downward 75 through said orifices.

3. A saveall for evaporators comprising a diaphragm adapted to divide the evaporator below the vapor outlet thereof, said diaphragm having a central discharge opening and a series of drainage orifices about 80 its marginal edge adjacent the wall of the evaporator, a deflector plate mounted above the opening, arcuate deflector blades extending between the diaphragm and the deflector plate and disposed about said central opening to direct the vapor laterally in a whirling course toward the wall of the evaporator, and baffle plates overhanging the drainage openings to arrest liquid entrained in the vapor and direct the liquid 85 90 95 through said orifices.

In testimony whereof I affix my signature.

ERNST W. KOPKE.
